UNITED STATES PATENT OFFICE.

ANTHONY VANDERVELD, OF GRAND RAPIDS, MICHIGAN, ASSIGNOR TO CLIPPER BELT LACER COMPANY, A CORPORATION OF MICHIGAN.

BELT-HOOK-FASTENING MACHINE.

1,254,948.

Specification of Letters Patent. Patented Jan. 29, 1918.

Application filed January 2, 1917. Serial No. 140,259.

To all whom it may concern:

Be it known that I, ANTHONY VANDERVELD, a citizen of the United States of America, residing at Grand Rapids, in the county of Kent and State of Michigan, have invented certain new and useful Improvements in Belt-Hook-Fastening Machines; and I do hereby declare the following to be a full, clear, and exact description of the invention, such as will enable others skilled in the art to which it appertains to make and use the same.

This invention relates to a machine for fastening belt hooks or staples into the ends of belts, it being designed for use with the common and well known Webb type of belt fasteners. In the process of fastening a plurality of belt hooks or staples in the end of a belt it is desirable that in the final attachment of staples to the belt end, the legs thereof be embedded in the belt end, this requiring a very heavy pressure or force applied to the belt staples. My invention has for one of its objects the provision of mechanism including a relatively stationary jaw or anvil and a movable pressure jaw between which the belt hooks or staples are bent for attachment to the end of a belt, and of mechanism for operating the pressure jaw toward the anvil so that on the beginning of its movement the pressure jaw moves at a relatively high rate of speed which diminishes as the pressure jaw moves toward the anvil until at the final portion of its movement toward the anvil it is relatively very slow. With the mechanism for actuating the same operated at a constant speed and under a constant force the pressure which may be transmitted by the jaw in the final portions of its movement is very great. A further object of the invention consists in the provision of novel mechanism for actuating the pressure jaw which may be quickly and easily operated by means of a crank and gearing connections interposed between the crank and the pressure jaw. Many other objects and purposes together with novel mechanism for attaining the same will be apparent as my invention is disclosed, reference being had to the accompanying drawings, in which;

Figure 1 is a plan view of the machine.

Fig. 2 is a vertical section taken longitudinally therethrough.

Fig. 3 is an end elevation looking at the 55 left hand end of Fig. 2.

Fig. 4 is a fragmentary enlarged section showing the anvil and the device mounted adjacent said anvil for holding the belt hooks or staples in parallel relation to each 60 other.

Fig. 5 is a plan of the anvil.

Fig. 6 is a rear elevation thereof.

Fig. 7 is a plan view of the staple holding bar and,

Fig. 8 is a front elevation thereof.

Like reference characters refer to like parts throughout the several views of the drawings.

In the construction of the machine a support is provided, preferably as a casting having spaced apart sides 1 and 2 connected at their lower edges by cross pieces 3. A shaft 4 is mounted between the sides 1 and 2 at the upper rear corner thereof, as shown 70 in Figs. 1 and 2, and carries thereon a pinion 5 and rollers 6 each of which is provided with a flange 7. Pinion 5 is keyed to the shaft while the rollers 6 are loosely mounted thereon, the pinion being interposed between the rollers and flanges 7 formed on the rollers at each end of the pinion.

A bar 8 is fixed to one end of shaft 4 and provided at each end with a handle 9 for manual operation thereof. In front of the 85 shaft 4 a second shaft 10 is mounted between the sides 1 and 2 of the support, on which a pinion 11 is loosely mounted, said pinion being of a length equal to the distance between the sides 1 and 2. A gear 12 considerably larger in diameter than the pinion 11 is passed over said pinion and meshes with the pinion 5 heretofore described, it being apparent that the pinion 11 extends for a distance to each side of the gear 12. A 90 pair of racks 13 mesh with the pinion 11, one at each side of the gear 12, and at their rear edges bear against the rollers 6, being held between flanges 7 of said rollers and the sides 1 and 2. Each rack at its lower end is 100 pivotally connected to the rear end of a member 14, said members being pivotally connected at their front ends to the sides 1 and 2 of the support as shown. Each of the members 14 on its upper edge is formed with 105 a curved surface as best shown in Fig. 2.

A lever 15 is pivotally mounted between its ends on the support on shaft 16. The

rearwardly extending portion of said lever is relatively long and on its end carries two rollers 17, one on each side, which bear against the upper edges of the members 14 heretofore described, the forwardly extending portion 15^a of the lever passes beyond the front edges of sides 1 and 2 and is formed into a bearing to receive a shaft 18 on which are pivotally mounted jaw supports 19, one at the outside of each of the sides 1 and 2 and extending upwardly and to the rear and then curved forwardly, there being a pressure jaw 20 secured to and between and on the under side of said jaw members at their upper ends. Rollers 21 are mounted upon a shaft 22 which is interposed between and connected to said jaw members back of the pressure jaw. These rollers ride on the upper edges of the sides 1 and 2 of the supports which are formed at such points to properly guide the rollers and the jaw members with which they are associated.

A bar 23 is cast integral with and is located between the front edges of the sides 1 and 2, it carrying on its upper surface a hardened plate or anvil 24 which is permanently secured in any suitable manner. Said anvil at its rear edge is formed with a series 30 of spaced tongues 25. Directly back and a little above the anvil 24 a bar 26 is located, it having rearwardly projecting ears 27 through which a pin 28 passes for pivotal mounting of the same between the sides 1 and 2 of the support. The forward edge of the member 26 is likewise fashioned with a series of spaced tongues 29 adapted to enter the slots between the tongues 25 previously described. Normally the slotted bar 40 26 is elevated by a coil spring 30 interposed between its lower side and the bar 23 until stopped by contact of shoulders 31 on said bar against the forward edges of the sides 1 and 2. Holes in alignment are made 45 through the tongues 29 whereby a pin 32 may be removably inserted through all of the holes for the purpose of retaining the belt hooks or staples 33 in place in parallelism to be acted upon by the pressure 50 jaw 20.

In operation a plurality of belt hooks or staples 33 sufficient for the width of the belt end are inserted in the slots between tongues 29 said staples each having diverging arms which terminate in attaching prongs turned toward each other. The opposite ends of the arms of a staple are connected by an integral curved bend or bite in front of which the retaining pin 32 passes 60 as shown in Fig. 4. The belt end 34 to which the staples are to be secured is inserted between the prongs and one of the handles 9 grasped to turn shaft 4 whereupon racks 13 are elevated carrying members 14 therewith as shown in Fig. 2 and causing a

corresponding elevation of the rear end of lever 15 and a depression of the forward end of the arm 15^a thereof. In this manner the jaw members 19 are moved from the dotted line position indicated in Fig. 2 to the full line position. It is apparent that during the fore part of the movement during which practically no work is being done, the elevation of the rear end of levers 15 and the corresponding forward and downward movement of the pressure jaw 20 is relatively rapid. But as the jaw 20 comes into contact with the upper arms of the staples 33 the movement of the jaw decreases and becomes increasingly slower. With the continuation of the movement of the pressure jaw the upper arms of the belt hooks or staples are bent downward and the attaching prongs thereon inserted into the end of the belt and at the same time the attaching prongs on the lower arms lying on the anvil 24 are inserted into the end of the belt from the opposite side. When this operation has begun it is not necessary to thereafter hold the belt end with one hand and both handles 9 may be grasped for operation of the mechanism whereby a very heavy pressure against the arms of the staples and against the end of the belt 34 may be produced said arms of the staple being easily embedded so as to lie flush with the surfaces of the belt end. At the same time as the staples are attached to the belt end, the member 26 is depressed and the force of spring 30 overcome so that the proper position of the curved portions of the belt staples with respect to the end of the belt is secured, this being of advantage in permitting use of the machine with belt hooks and staples of varying sizes.

I claim:—

1. In a machine of the character described, a support, an anvil on the support, means for holding a plurality of belt staples in parallel relation to each other on the anvil, a lever pivotally mounted between its ends on the support below the anvil, jaw supporting arms pivotally connected to one end of the lever and extending above the anvil, a pressure jaw connected to said arms, and means for elevating the opposite end of the lever to thereby move the pressure jaw toward the anvil, substantially as described.

2. In a machine of the character described, a support, an anvil on the support, means for holding a plurality of belt staples in parallel and spaced relation to each other lengthwise of the anvil, a lever pivotally mounted between its ends on the support below the anvil, jaw supporting arms pivotally connected to one end of the lever and extending above the anvil, a pressure jaw carried by said arms, means for elevating the opposite end of the lever to thereby move the pressure jaw toward the anvil, and

means to guide the jaw to proper position above the anvil, substantially as described.

3. In a machine of the character described, a support, an anvil lying trans-

5 versely of and at the front of the support, jaw carrying arms pivotally mounted at one end below the anvil and extending upwardly and to the rear and then curved forward at their upper ends, a pressure jaw 10 carried at the upper ends of said arms, and means for moving said pressure jaw toward the anvil with a decreasing rate of speed, said moving means being operated at a constant speed, substantially as described.

15 4. In a machine of the character described, a support, an anvil lying transversely of and at the front of the support, jaw carrying arms pivotally mounted at one end below the anvil, said arms lying 20 along the sides of the support and extending upwardly and to the rear above the anvil, a pressure jaw carried at the upper ends of the arms, a shaft connecting the arms, rollers on the shaft bearing against 25 the front edges of the support, and means for moving the jaw toward the anvil, substantially as described.

5. In a machine of the character described, a support including spaced apart 30 sides, an anvil lying transversely of and at the front edges of the support, a lever lying between said sides of the support and pivotally mounted between its ends below the anvil, jaw supporting arms pivotally mounted 35 at the forward end of the lever, said arms lying along the outer sides of the sides of the support and extending upwardly and to the rear above the anvil, a pressure jaw attached at the upper ends of said arms, 40 rollers movable with the arms and riding against the front edges of said sides above the anvil, means for elevating the rear end of the lever, and means for holding a plurality of belt hooks in spaced and parallel 45 relation on the anvil below the pressure jaw.

6. In a machine of the character described, a support including spaced apart sides, an anvil lying transversely of and 50 at the front edges of the support, a lever pivotally mounted between its ends between the sides of the support below the anvil, jaw carrying arms pivotally connected to the forward end of the lever, said arms extending 55 upwardly and to the rear above the anvil, a pressure jaw attached to the upper ends of the arms, means for holding a plurality of belt hooks in parallel and spaced relation lengthwise of the anvil and below 60 the jaw, members having curved upper edges pivotally mounted on said sides of the support on the inner sides thereof, rollers on the rear end of the lever arranged to bear against said curved edges of the 65 members, and means for turning said mem-

bers about their pivotal mount to thereby elevate the lever and progressively increase the force exerted thereon, substantially as described.

7. In a machine of the character de- 70 scribed, a support including spaced apart sides, an anvil lying transversely of and at the front of the support, a lever pivotally mounted between its ends between the sides of the support below the anvil, jaw supporting arms pivotally connected to the forward end of the lever, said arms extending upwardly and to the rear above the anvil, a pressure jaw attached to the upper ends of the arms, means for holding a plurality of 80 belt hooks in parallel and spaced relation lengthwise of the anvil and below the jaw, members having curved upper edges pivotally mounted on the support on the inner sides thereof, rollers on the rear end of the 85 lever arranged to bear against said curved edges of the members, racks connected to the free ends of said members and extending upwardly, a pinion rotatively mounted between the sides of the support with which 90 said racks engage, and means for rotating the pinion.

8. In a machine of the character de- 95 scribed, a support, an anvil on the support, means for holding a plurality of belt hooks in parallel and spaced relation to each other 100 lengthwise of the anvil, a lever pivotally mounted between its ends on the support below the anvil, jaw supporting arms pivotally connected to the forward end of the lever and extending above the anvil, a pressure 105 jaw attached to said arms, members located one at each side of the rear end of the lever and pivotally connected to the support at one end, rollers at the rear end of the lever arranged to bear against edges of said members, racks pivotally connected to the free 110 ends of the members, a pinion rotatively mounted on the support with which the racks engage, and means for driving the pinion, substantially as described.

9. In a machine of the character de- 115 scribed, a support including spaced apart sides, an anvil lying transversely of and at the front of the support, a lever pivotally mounted between its ends between the sides of the support and below the anvil, jaw carrying arms pivotally connected to the forward end of the lever, said arms extending 120 upwardly and to the rear above the anvil, a pressure jaw attached to the upper ends of the arms, means for holding a plurality of belt hooks in parallel and spaced relation lengthwise of the anvil and below the pressure jaw, members located one at each side 125 of the rear end of the lever and pivotally connected at their front ends to the sides of said support, rollers mounted at the rear end of the lever each adapted to bear against an edge of one of said members, a shaft 130

rotatively mounted on the support adjacent its upper portion, a pinion on the shaft, a gear fixed on the pinion between the ends thereof, racks connected to said members 5 engaging with the pinion at each side of the gear, a shaft on the support back of the first mentioned shaft, a pinion fixed thereon meshing with the gear, and a pair of rollers loosely mounted on the shaft at each end of 10 the pinion, each of said rollers being provided with a flange at the end adjacent said pinion, substantially as described.

10. In a machine of the character described, a support, a bar located transversely 15 of the support, a plate connected to and resting against the bar, said plate at one edge being provided with a plurality of projecting tongues separated by slots, a bar pivotally mounted on the support adjacent the 20 plate and similarly formed at one edge with a plurality of projecting tongues separated by slots, the tongues of the plate and bar being received in the slots of the bar and plate respectively, said tongues on the bar 25 being also provided with aligned openings

adapted to receive a pin therethrough, spring means tending to elevate the bar, and shoulders on the pivoted bar to engage against the support to limit the elevation of the bar.

11. In a machine of the character described, a support, a bar located transversely of the support, a plate connected to and resting against the upper side of the bar, said plate on its rear edge being formed with 35 a plurality of projecting tongues separated by slots, and a bar pivotally mounted on the support back of the plate and similarly formed at its front edge with a plurality of projecting tongues separated by slots, said 40 tongues on the bar being provided with aligned openings adapted to removably receive a pin at a distance in front of the pivotal connection of the bar to the support, the tongues of the plate and bar being received in the slots of the bar and plate respectively, substantially as described.

In testimony whereof I affix my signature.

ANTHONY VANDERVELD.
